UNITED STATES PATENT OFFICE

145,473

DESIGN FOR A HANDBAG

Bernard Calem, New York, N. Y.

Application March 13, 1946, Serial No. 127,419

Term of patent 3½ years

(Cl. D87—3)

To all whom it may concern:

Be it known that I, Bernard Calem, a citizen of the United States and a resident of New York, county of Bronx, and State of New York, have invented a new, original, and ornamental Design for a Handbag, of which the following is a specification, reference being had to the accompanying drawing, forming a part thereof, in which:

Fig. 1 is a perspective view of the handbag embodying the new design, showing the same in closed position and showing the top, front and side thereof; and

Fig. 2 is a perspective view thereof in open position showing the top, front and other side.

I claim:

The ornamental design for a handbag, substantially as shown.

BERNARD CALEM.
